CENTRIFUGAL SPINDLE CLUTCH

Jules L. Laquerre, 913 Social St., and Amato F. Rosati,
63 Rutland St., both of Woonsocket, R.I.
Filed Jan. 22, 1960, Ser. No. 4,069
6 Claims. (Cl. 192—105)

This invention relates to a novel and improved centrifugal clutch for the spindles of such as spinning frames, twisting frames, and the like.

The primary object of the invention is to provide a more efficient and rugged device of the kind indicated, which involves a cap and a body which are in spaced relation to each other and are connected for rotation together by guide means which extends therebetween, the guide means serving as mounting and positioning means for expandible jaw means which are centrifugally expandible to grip the interiors of tubes, bobbins and the like engaged on the device.

Another object of the invention is the provision of a more versatile device of the character indicated above, wherein the body thereof is adapted to be locked to an associated spindle to mount the device thereon, and the cap thereof is devoid of such locking means, and wherein the centrifugal jaw means can be of different forms and be composed of selected numbers of jaw elements.

A further object of the invention is to provide a device of the character indicated above wherein the centrifugal jaw means comprises a plurality of flat discs which are mounted on the guide means, in stacked and touching relationship, the discs being similar but being engaged with the guide means in differing circumferential positions, so as to present, at differing points spaced circumferentially around the device, gripping edge portions of different discs.

Other important objects and advantageous features of the invention will be apparent from the following description and the accompanying drawings, wherein, for purposes of illustration only, a specific form of the invention is set forth in detail.

In the drawings:

FIGURE 1 is a perspective view showing a clutch device of the invention installed, on a spindle;

FIGURE 2 is an enlarged vertical transverse section taken on the line 2—2 of FIGURE 1;

FIGURE 3 is a horizontal section taken on the line 3—3 of FIGURE 1;

FIGURE 4 is an enlarged fragmentary side elevation showing a device of the invention installed on a spindle, and a tube, shown in section, engaged on the device;

FIGURE 5 is a horizontal section taken on the line 5—5 of FIGURE 4; and

FIGURE 6 is an exploded perspective view of the device, before assembly.

Referring in detail to the drawings, wherein like numerals designate like parts throughout the several views, the illustrated clutch device, general designated 10, comprises a base 12, a cap 14, a centrifugal jaw assembly 16, and jaw assembly mounting assembly 18 on the base 12.

The base 12 comprises a relatively thick and preferably solid, circular flat body 20 having an axial bore 22 extending therethrough, to slidably receive the spindle 24 of such as a spinning or twisting frame (not shown). For locking the base 12 on a spindle 24, suitable means is provided, preferably in the form of a locking stud 26, threaded in a radial bore 28 formed in the body 20 and entering the axial bore 22.

Surrounding the bore 22 and fixed to the upper surface 30 of the base body 20, is an upstanding, relatively thin-walled tube 32 having an open upper end 34, which is a component of the mounting means 18. The tube 32

2

has a vertical bore 36 the same in size as and registered with the body bore 22.

The mounting means 18 further comprises a plurality of, preferably three, similar round rods 38, of relatively small diameter, which extend through bores 40 formed through the base body 20 and are uniformly spaced from the tube 32 and equally circumferentially spaced from each other around the body 20. The body 20 has a peripheral edge 42 which is slightly smaller in diameter than the interior surface 44 of a bobbin or tube 46 which is to be mounted on an and secured to a spindle 24, as shown in FIGURE 4.

The cap 14 comprises a circular body 48, preferably of the same thickness and diameter as the base body 20, which is formed with an axial bore 50 to receive the spindle 24, and with a plurality of uniformly eccentric smooth bores 52, which are of the same size as and are positioned to receive the upper ends of the rods 38 of the base 12.

As shown in FIGURE 2, the axial bore 50 of the cap body 48 has a counterbore 54 opening to the lower or under surface 56 of the cap body 48, to receive an upper end portion of the base tube 32, with the upper end 34 of the tube abutting the shoulder 58 defined at the upper end of the counterbore 54, whereby the cap 14 is maintained in a predetermined spaced position above the base body 20. The rods 38 are of such length that when the base 12 and the cap 14 are assembled, related ends of the rods project above the upper surface 60 of the cap body 48 and the undersurface 62 of the base body 20, against which the rod ends are riveted or peened, as indicated at 64 and 66, respectively.

In this connection it is to be noted that the rods 38 can be secured to the base 12 and the cap 14 in any other desired manner which enables disconnection therefrom from the cap 14 and/or the base 12, without significant damage thereto, for the purpose of enabling the substitution, when wanted, of different forms of centrifugal jaw means, or different numbers of jaw elements or components.

The illustrated centrifugal jaw assembly 16 comprises a plurality of, such as six, similar relatively thin flat circular discs 68, each being an independent jaw element, which are preferably slightly smaller in diameter than the base 12 and the cap 14, and have peripheral edges 70. Each jaw element 68 has a circular axial opening 72 which is larger in diameter than, and is loosely engaged on the base tube 32, so that the jaw elements have predetermined limited freedom to be moved, by centrifugal force, when the spindle 24 and the device 10 are rotated, laterally relatively to the tube 32, so as to extend a portion of an edge 70 beyond the peripheral edges of the base 12 and the cap 14 and grip a portion of the interior surface 44 of a bobbin or tube 46 engaged on the device 10, as shown in FIGURES 4 and 5.

The jaw elements 68 are prevented from rotating relative to the base 12 and the cap 14 and guided in radial inward and outward movements relative thereto, by engagement with related ones of the rods 38, of a pair of parallel chordal slots 74 which have closed inner ends 80 located on diameters of the elements and open ends 82 at the gripping edges 70 thereof; and of single slots 84 which are parallel to and are spaced midway between the slots 84 and open to the axial openings 72 of the jaw elements, at the sides of the elements opposite the slots 84. The closed ends 88 of the single slots 84 and the closed ends 80 of the slots 84 are located so that undue projection of the jaw elements 68 in their centrifugally actuated gripping movements relative to the base 12, the cap 14, and the mounting assembly 18, is precluded, by engagement of the closed ends of the slots with related

rods 38, or, optionally by engagement of the jaw element openings 72 with the tube 32.

As shown in FIGURE 2 and 4, the jaw elements 68 bear loosely against each other and the stack of jaw elements is loosely confined between the facing surfaces of the base 12 and the cap 14, so that freedom of independent centrifugal movements of the jaw elements is assured.

As shown in FIGURES 2, 3, 5 and 6, adjacent jaw elements 68 are engaged on the rods 38, so that these elements and their slots 74 and 84 are disposed at different angles of at least forty-five degrees relative to each other. Depending upon the number of jaw elements 68 used, alternate jaw elements are arranged at 120 degrees relative to each other, as shown in FIGURES 5 and 6, the end in view being the provision of gripping edge portions 90, in the areas of the single slots 84, which, when the elements are centrifugally projected, will make equally circumferentially spaced gripping contacts with the interior surface 44 of the bobbin or tube 46, as shown in FIGURES 4 and 5. With this understanding of the functional structures of the elements 68, it will be evident that these elements can be otherwise than symmetrically circular. The six jaw elements 68 are illustrated as composed of three sets of two, the elements of each set being disposed at angles of 120° relative to each other, with the adjacent elements of each set disposed at 120° relative to each other.

It is to be noted that because of the relatively small frictional surface engagements presented by the edges of the slots 74 and 84 in engagement with the rods 38, and the loose engagements of the surfaces of adjacent jaw elements 68, and the loose contacts between jaw elements and the facing surfaces of the base 12 and the cap 14, the jaw elements have maximum freedom of centrifugal movement into gripping engagements with the interior of a bobbin or tube, which assures maximum grip consistent with the speed of rotation of a spindle 24, of the jaw elements with the bobbin or tube. Further, making the slots 74 and 84 wide enough to avoid binding thereof on the rods 38, provides for conformance of the gripping edge portions 90 with the interior surface of a bobbin or tube, so more effective grip of the elements 68 thereon is produced.

Although there has been shown and described herein a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. A centrifugal clutch comprising a base, a cap spaced from the base, mounting means extending between and fixed to the base and the cap, and a centrifugal jaw assembly mounted on said mounting means, said jaw assembly comprising a stack of flat jaw elements circumposed on the mounting means between the base and the cap, said jaw elements having eccentric principal mass portions having gripping edges which are spaced from each other around the clutch, said base, said cap, and said jaw elements having aligned axial openings therethrough for receiving a spindle, and spindle engaging locking means on said clutch, said mounting means comprising circumferentially spaced rods extending between the base and the cap, said jaw elements have chordal slots severally engaged with the rods, the slots of adjacent jaw elements being angularly displaced relative to each other.

2. A centrifugal spindle clutch comprising a circular flat base, a circular flat cap, said base and said cap being spaced from each other and being smaller in diameter than a tube to be engaged on the clutch, rods extending between and fixed to the base and the cap, an axial spindle receiving tube fixed to the base and extending to

the cap, said rods being concentrically spaced around the tube and circumferentially spaced from each other, said base and said cap having aligned axial spindle receiving openings registered with the bore of said tube, a jaw assembly positioned and loosely confined between said base and said cap, said assembly comprising a plurality of relatively thin independently movable jaw elements having axial openings larger in diameter than and loosely engaged on said tube, said jaw elements having parallel chordal slots severally engaged on related ones of said rods, said elements having eccentric principal mass portions having gripping edges, and means on the base for locking the clutch on a spindle.

3. A centrifugal spindle clutch comprising a circular flat base, a circular flat cap, said base and said cap being spaced from each other and being smaller in diameter than a tube to be engaged on the clutch, rods extending between and fixed to the base and the cap, an axial spindle receiving tube fixed to the base and extending to the cap, said rods being concentrically spaced around the tube and circumferentially spaced from each other, said base and said cap having aligned axial spindle receiving openings registered with the bore of said tube, a jaw assembly positioned and loosely confined between said base and said cap, said assembly comprising a plurality of relatively thin independently movable jaw elements having axial openings larger in diameter than and loosely engaged on said tube, said jaw elements having parallel chordal slots severally engaged on related ones of said rods, said elements having eccentric principal mass portions having gripping edges, and means on the base for locking the clutch on a spindle, the slots of adjacent discs being angularly displaced relative to each other with the gripping edge portions of the discs circumferentially spaced around the clutch.

4. A centrifugal spindle clutch comprising a circular flat base, a circular flat cap, said base and said cap being spaced from each other and being smaller in diameter than a tube to be engaged on the clutch, rods extending between and fixed to the base and the cap, an axial spindle receiving tube fixed to the base and extending to the cap, said rods being concentrically spaced around the tube and circumferentially spaced from each other, said base and said cap having aligned axial spindle receiving openings registered with the bore of said tube, a jaw assembly positioned and loosely confined between said base and said cap, said assembly comprising a plurality of relatively thin independently movable jaw elements having axial openings larger in diameter than and loosely engaged on said tube, said jaw elements having parallel chordal slots severally engaged on related ones of said rods, said elements having eccentric principal mass portions having gripping edges, and means on the base for locking the clutch on a spindle, the slots of adjacent jaw elements being angularly displaced relative to each other with the gripping edge portions of the jaw elements circumferentially spaced around the clutch, said rods being three in number and being spaced from the peripheral edges of the base and the cap, and said slots consisting of a pair of slots having closed inward ends and outward ends which open to the edges of the jaw elements, and a single second slot located between the first slots, said single slot having a closed outward end and an inner end which opens to the axial openings of the jaw elements.

5. A centrifugal clutch comprising a circular base, a circular cap axially aligned with and spaced from said base, said base and said cap having aligned axial openings, said base having an axial tube fixed around its axial opening and extending to and bearing against the cap around the axial opening of the cap, a plurality of circumferentially spaced rods spacedly surrounding said tube and extending between the base and the cap, a plurality of flat centrifugal jaw elements, said discs having central openings larger in diameter than and loosely receiving said tube, said elements being movable relative to each other be-

tween the base and the cap and laterally relative to the base and the cap, said elements having pairs of parallel chordal slots having outward ends opening to the peripheries of the elements, and single diametrical slots located between said chordal slots, said elements having eccentric principal mass portions located in the regions of said single slots and having peripheral gripping edges.

6. A centrifugal clutch comprising a circular base, a circular cap axially aligned with and spaced from said base, said base and said cap having aligned axial openings, said base having an axial tube fixed around its axial opening and extending to and bearing against the cap around the axial opening of the cap, a plurality of circumferentially spaced rods spacedly surrounding said tube and extending between the base and the cap, a plurality of flat centrifugal jaw elements, said discs having central openings larger in diameter than and loosely receiving said tube, said elements being movable relative to each other

5

10

between the base and the cap and laterally relative to the base and the cap, said elements having pairs of parallel chordal slots having outward ends opening to the peripheries of the elements, and single diametrical slots located between said chordal slots, said elements having eccentric principal mass portions located in the regions of said single slots and having peripheral gripping edges, said chordal slots having closed inward ends, said single slots having inward ends opening to the jaw element openings and closed outward ends.
